UNITED STATES PATENT OFFICE.

GEORGE W. BLANK, OF ST. CHARLES, MINNESOTA.

GRAIN-DISTRIBUTER.

1,309,315.

Specification of Letters Patent.

Patented July 8, 1919.

Application filed December 24, 1918. Serial No. 268,158.

To all whom it may concern:

Be it known that I, GEORGE W. BLANK, a citizen of the United States, residing at St. Charles, in the county of Winona and State 5 of Minnesota, have invented certain new and useful Improvements in Grain-Distributers, of which the following is a specification, reference being had to the accompanying drawings.

10 This invention relates to certain improvements in grain distributers, and has relation more particularly to a device of this general character especially designed and adapted for use in connection with grainaries, and it is an object of the invention to provide a novel and improved device of this general character which may be readily moved laterally or swung horizontally. It is another object of the invention to provide a 15 novel and improved device of this general character including a hopper and a delivery chute connected one to the other through the medium of an elbow, and which elbow consists of a plurality of hingedly connected 20 and telescoping sections in order to permit the delivery chute to be readily moved laterally.

An additional object of the invention is to provide a device of this general character 30 including a hopper and a delivery chute co-acting therewith, together with means for connecting the chute to the hopper in a manner whereby the chute may be readily and conveniently swung horizontally.

35 The invention consists in the details of construction and in the combination and arrangement of the several parts of my improved grain distributer whereby certain important advantages are attained and the device rendered simpler, less expensive and otherwise more convenient and advantageous for use, as will be hereinafter more fully set forth.

The novel features of my invention will 45 hereinafter be definitely claimed.

In order that my invention may be the better understood, I will now proceed to describe the same with reference to the accompanying drawings, wherein:

50 Figure 1 is a fragmentary vertical sectional view taken through a distributer constructed in accordance with an embodiment of my invention, the discharging end portion of a feed spout being shown in elevation:

55 Fig. 2 is an enlarged fragmentary sec-

tional view taken substantially on the line 2-2 of Fig. 1;

Fig. 3 is a view in bottom plan of the hopper as comprised in my improved distributor;

Fig. 4 is a view in plan of the sections comprised in the holding collar as herein employed, said sections being shown separated;

Fig. 5 is a view in perspective of one of 65 the sections of the elbow detached;

Fig. 6 is a view in perspective of a second section of the elbow as herein embodied, detached; and

Fig. 7 is a view in perspective of a third 70 section comprised in the elbow detached.

As disclosed in the accompanying drawings, H denotes a hopper herein disclosed as substantially square in top plan, and which has its upper margins defined by the outwardly directed flanges 1 adapted to be secured in any desired manner with a support S. The side walls of the hopper H are reduced in a manner whereby the bottom of the hopper H is provided with a circular 80 discharge opening 2, and this opening is defined by an outstanding annular flange 3.

E denotes a section of an elbow which is segmental in side elevation, and which has its upper end portion defined by the outstanding flanges 4 adapted to underlie and contact with the flange 3 of a hopper H hereinbefore referred to. The flanges 4 are of a width to extend beyond the outer margin of the flange 3 and through said extended portions are disposed the bolts 5 or the like, and which bolts are engaged with the marginal portions of the holding collar C.

As is particularly illustrated in Fig. 4, 95 the holding collar C comprises two sections 6 substantially duplicate in construction, and which, when in applied position conforms to the configuration of the upper end of the section E of the elbow. The opposed marginal 100 portions of the sections 6 are cut away as at 7 so that the sections 6 of the collar will readily swing the lower portion of the hopper H when said collar is in applied position. It is to be understood that the inner portions 105 of the side of the sections 6 of the collar will overlap and certain of the bolts 4 will extend through said overlapping portions in order to maintain the collar C in applied position.

When the section E is engaged with the collar C as hereinbefore described, it will be self evident that said section E is capable of horizontal swinging movement, as the flange 4 of the section E and the holding collar C coact with the flange 3 to effect a swivel connection between the section E and the hopper H.

E' denotes a second elbow section having each of its opposite ends 8 arcuate in cross section, with its lower end disposed on a curvature concentric to the smaller or restricted end of the elbow section E. The opposite end portion 8 is disposed on a curvature substantially concentric to the outer side margin of the first named end portion 8. The inner or upper end portion of the second curved end 8 of the section E' is provided with the knuckles 9 which intermesh with the knuckles 10 arranged at the smaller end of the section E and disposed through said knuckles 9 and 10 is a pintle 11. By this arrangement it will be readily perceived that the section E' is capable of lateral swinging movement relative to the elbow section E and that said sections E and E' telescope one relatively to the other.

Similar adjacent ends of the elbow sections E and E' at adjacent marginal portions are provided with the flanges 12 adapted to interlock whereby the outward relative movement of said sections E and E' is limited. The side marginal portions of the adjacent ends of the sections E and E' are also provided with similar flanges 12' coacting or intermeshing for the same purpose.

E² denotes a third section of the elbow as herein included and the upper end of the lower wall of said section is provided with the knuckles 14 intermeshing with the knuckles 15 arranged at the outer portion of the lower end 8 of the section E' and disposed through said knuckles 14 and 15 is a pintle 16 whereby the section E² is capable of lateral swinging movement independent of the section E'. The top wall of the section E² has its upper portion outwardly directed as indicated at 17 on a curvature concentric to the hinged or pivotal connection afforded by the pintle 16 so that the upper end portion of the section E and the upper end portion of the section E² will telescope one within the other in order to effect the

desired relative adjustment between the sections E' and E². The adjacent marginal portions of the sections E' and E² are also provided with the flanges 18 which are adapted to interlock so that the outward swinging movement of the section E² relative to the intermediate section E' will be limited.

Suitably engaged with the outer or lower end portion of the section E² is a chute 19 which may be of any desired length or configuration.

In view of the particular construction of the elbow as afforded by the sections E, E' and E², it will be at once obvious that the chute 19 may be laterally moved or horizontally swung in a manner to effect the desired distribution of grain to any part of a granary so that the storage of grain is materially facilitated.

From the foregoing description, it is thought to be obvious that a grain distributor constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

What is claimed is:

A distributor of the class described comprising a hopper, a chute, and an elbow connecting said hopper and chute, said elbow comprising an intermediate section, and end sections hingedly connected therewith at opposite ends and at opposite sides, said sections telescoping one within the other, the sections of the elbow being provided with interlocking flanges whereby the outward swinging movement of the end sections relative to the intermediate section is limited.

In testimony whereof I hereunto affix my signature in the presence of two witnesses.

GEORGE W. BLANK.
